BOILER RETURN SYSTEM

Donald B. Knight, Brooklyn, N. Y., assignor to
Refrigeration Research Corporation, Brooklyn,
N. Y., a corporation of New York

Application November 29, 1933, Serial No. 700,162

8 Claims. (Cl. 237—67)

This invention relates to boiler return systems and in particular to those systems wherein the condensed water is under the same pressure as the pressure in the boiler.

5 Heretofore when the steam has been condensed at a point below the water level in the boiler, it has been necessary to pump the water back into the boiler by mechanical means or to use an injector. In the first instance mechanical attention is required and, in the case of the steam 10 injector, there is a limit in the temperature of the water handled. In neither case is it feasible to operate continuously or without regard to the amount of condensed water collected.

15 It is the object of this invention to provide a continuously operating return system for heating plants, wherein the condensed water is under boiler pressure at a point below the water level in the boiler, this return system operating without valves or other moving parts.

20 Further objects and advantages of the invention will be apparent as it is described in further detail in connection with the drawing, the single figure of which is a diagrammatic illustration 25 of a boiler return system constructed in accordance with the present invention.

25 In the drawing, the boiler is shown at A and is heated by a burner B or other suitable means. C is a radiator which is situated below the level 30 of the water in the boiler and D is a container to which the water and steam may be delivered, this container being above the level of the water in the boiler. Water may be admitted to the container D through a valve E and discharged 35 therefrom through a valve F. The container D is connected to the boiler A by a pipe connection g which includes a trap G, which acts as a check as hereinafter explained, the trap comprising an enlarged leg G' which is connected 40 at its upper end by a leg g¹ with the lower end of the line g, and is connected at its lower end with the boiler A by a leg g². The leg G' is provided at its upper end with a vent cock g³. A pipe line I is provided to deliver steam from the 45 boiler to the radiator C, while a pipe line H serves to carry steam and water from the radiator C to the container D. The trap G is formed 50 as a double trap having the enlarged leg G' through which steam from the boiler may bubble without displacing water which is contained therein.

The system operates as follows:

55 Water from the mains is first admitted to the container D through the valve E. The valve F at the top of the container is opened to the sewer

so that the water flows freely into the container, first filling the trap G and entering the boiler, then rising and filling the container D. By regulating the rate of flow of the water from the mains entering the container D through the valve E the level in container D may be made to rise while the water is at the same time running from container D to the boiler through the line g and the trap G. Therefore, when any desired level is obtained in the boiler, the level may be permitted to rise in container D, finally filling the line H between the radiator and the container. If the pipe forming the line H is not of sufficient diameter to permit air and water to pass freely in opposite directions, the valve J 10 at the top of the radiator should be opened to permit the displaced air to escape while the line H is being filled. The valves E and F are then closed and the burner B is lighted, the valve E being closed to prevent more water from entering the system and the valve F being closed to prevent air from being sucked into the system. At this time the trap G is completely filled with water.

20 As the water boils in boiler A, steam passes 25 to the radiator C through the line I and displaces air in the radiator which escapes when the valve J is opened. When all of the air has been displaced, valve J is closed and the steam pressure 30 builds up in the boiler. Valve F is again opened 35 and water from the radiator is pushed out through H, D, and F, under the influence of the steam pressure in the boiler.

40 At the same time the level of water in the inner leg g² of the trap G is depressed, the column of water in the line H being counterbalanced 45 by the column of water in the line g and its connections. Inasmuch as steam passes through the lowest point of the line H it is apparent that the depression of the water level in the leg g² on the boiler side of the trap G would reach to the bottom of trap G if the lowest point of both line H and trap G were situated at the same level. Consequently the trap G might be located below the lowest point of the line H, but it is preferably formed, as shown in the drawing, as a double trap with an enlarged leg G' through which steam from the boiler may bubble without displacing all of the water therein. Steam from the boiler enters the bottom of the enlarged leg G' and passes to the top of the enlarged leg. Since the bubbles have volume the bubbles of steam displace some of the water in the enlarged leg in their passage upward. The water so displaced is forced through the leg g¹ 50 55

- of trap G. When the steam reaches the top of the enlarged leg it forms a body of steam in the upper end of the enlarged leg. Thence forward any steam bubbling in at the bottom of the enlarged leg forces a substantially equal volume of the steam pocketed at the top of the enlarged leg into the adjoining leg g^1 , depressing the column of water therein. The level of the water in this leg g of the trap, under the influence of the steam pressure, could descend until the bottom of the trap is reached if further steam could be admitted at the bottom of the enlarged leg. However, this condition cannot occur since the column of water in line H would then be counterbalanced not only by the water in container D and in the line g joining the bottom of container D and the trap G, but also by an additional column of water in the enlarged leg G' of the trap G. Consequently steam will blow through the line H before the column of water in the leg g^1 of trap G can reach the bottom. The double trap is provided with a petcock at the top of the enlarged leg to allow pocketed air to escape while the trap is being filled.
- When steam from the bottom of the radiator enters the line H, clearing it of water, and bubbling into the container D, the valve F at the top of the container may be closed, whereupon the water in the container flows by gravity into the boiler through the line g and trap G and is replaced by steam entering the container through the line H.

Inasmuch as steam is continually being condensed in the radiator C, short separated columns of this condensed water must also pass through the line H, as well as steam, and consequently the level in the line g does not fall to the point where the inner leg g^2 enters the boiler, but is elevated to a degree dependent upon the number and length of the separated columns of water passing upward in the line H, say to the level K—K.

The steam entering the container is condensed to water due to heat radiation. This continuous condensation automatically adjusts the pressure in the container D to a value sufficiently lower than the steam pressure in the boiler and radiator to draw up the short separated columns of condensed liquid in the line H, and the condensate, together with the water so drawn up from the radiator, flows back to the boiler through the line g and trap G.

The operation of the system proceeds indefinitely as long as heat is applied to the boiler, and after the operation is once instituted the trap G has no function whatever since the level in the line g then stands continually at the level K—K. The only function of trap G is to act as a device in starting up the operation to insure that at the outset steam shall blow through line H and not through trap G and line g . An equivalent purpose might be served by a check valve opening toward the boiler and closing toward container D, or by an extension of the connection g^1 between the boiler A and the container D to a point below the lowest point of line H as already suggested.

It will be noted that should the steam blow through line g instead of the line H at the outset it would continue to do so indefinitely and no water condensed in the radiator C could be returned to the boiler.

The requirement for the successful operation of the system is that the rate at which water is delivered through H from the radiator to the

container keeps pace with the rate at which steam is condensed within the radiator C.

If this condition is not obtained the short columns of water in H will become progressively longer and the level K—K will therefore rise progressively until the container D is filled with water. Steam can therefore no longer pass into the container and the flow through H ceases entirely.

To avoid this, the line H must be made of a generous rather than a small internal diameter and the radiating surface of the container D must be great enough to insure sufficient condensation of steam in container D so that the flow of steam through the line H is adequate and rapid.

The present invention has been embodied in a system wherein the pipes g , g^1 , g^2 , G and H are each of three-eighths inch iron pipe size and the pipe I of three quarter inch iron pipe size, the dimensions of tank D are seven inches by twelve and one-half inches and the elevation between the lowest point of the pipe H and the bottom of tank D is fifty nine inches. The height of the connection of pipe g^2 to the boiler A is thirty six and one-half inches above the lowest point of the system and the height of the intermediate leg of the pipe G is fifteen inches.

The radiator C, in the system in which the invention has been embodied, consists of two radiators each thirty two inches high, one of twelve sections and the other of fifteen sections. Obviously, the invention may be embodied in systems with dimensions other than those specified above and the foregoing are given as the specific dimensions of a construction which has been operated in accordance with the present invention.

While the invention has been described with specific reference to the accompanying drawing, it is not to be limited, save as defined in the appended claims.

I claim as my invention:

1. A boiler return system comprising a boiler, a radiator below the water level of the boiler and connected to the boiler, a container of the closed type above the level of the water in the boiler and connected to the lower portion of the radiator, and a connection between the container and the boiler including a device to prevent the blowing through of steam from the boiler in the initial operation of the system.

2. A boiler return system comprising a boiler, a radiator below the water level of the boiler and connected to the boiler, a container of the closed type above the level of the water in the boiler and connected to the lower portion of the radiator, and a connection between the container and the boiler including a device to prevent the blowing through of steam from the boiler in the initial operation of the system, the size of the container between the radiator and container being relatively large and the radiating surface of the container sufficiently great to insure sufficient condensation of steam in the container to permit adequate flow of steam through the said connection.

3. A boiler return system comprising a boiler, a radiator below the water level of the boiler, piping connecting the top of the boiler and the radiator, a container of the closed type above the level of the water in the boiler, piping connecting the bottom of the radiator with the top of the container, and a connection between the bottom of the container and the top of the boiler including a device to prevent the blowing through

of steam from the boiler in the initial operation of the system.

4. A boiler return system comprising a boiler, a radiator below the water level of the boiler, piping connecting the top of the boiler and the radiator, a container of the closed type above the level of the water in the boiler, piping connecting the bottom of the radiator with the top of the container, and a connection between the bottom of the container and the top of the boiler including a double trap to prevent the blowing through of steam from the boiler in the initial operation of the system.

5. A boiler return system comprising a boiler, a radiator below the water level of the boiler, piping connecting the top of the boiler and the radiator, a container of the closed type above the level of the water in the boiler, piping connecting the bottom of the radiator with the top of the container, and a connection between the bottom of the container and the top of the boiler including a double trap to prevent the blowing through of steam from the boiler in the initial operation of the system, the double trap having an enlarged leg.

6. A boiler return system, comprising a boiler, a radiator below the water level of the boiler, piping connecting the top of the boiler and the radiator, a container of the closed type above the level of the water in the boiler, piping connecting the bottom of the radiator with the top of the

container, means to introduce water into the container, means to vent the container, and a connection between the bottom of the container and the top of the boiler including a trap to prevent the blowing through of steam from the boiler in the initial operation of the system.

7. A boiler return system comprising a boiler, a radiator below the water level of the boiler and connected to the boiler, a container of the closed type above the level of the water in the boiler and connected to the lower portion of the radiator, and a connection between the container and the boiler including a trap to prevent the blowing through of steam from the boiler in the initial operation of the system, the size of the connection and radiating surface of the container being such that the rate at which water is delivered through the connection to the container is proportional to the rate at which water is condensed within the radiator.

8. The method of circulating fluid in a boiler return system comprising introducing steam into a radiator below the level of water in a boiler, condensing the steam in the radiator, reducing by condensation the pressure in a closed container above the level of the water in the boiler and thereby causing condensed steam in the radiator to be drawn into the container, and delivering the water in the container to the boiler.
